UNITED STATES PATENT OFFICE.

MARCUSS D. MOORE, OF WAVELAND, INDIANA.

RAILWAY-SWITCH.

SPECIFICATION forming part of Letters Patent No. 683,479, dated October 1, 1901.

Application filed April 5, 1900. Serial No. 11,577. (No model.)

To all whom it may concern:

Be it known that I, MARCUSS D. MOORE, a citizen of the United States, residing at Waveland, in the county of Montgomery and State of Indiana, have invented new and useful Improvements in Railway-Switches, of which the following is a specification.

This invention relates to improvements in railway-switches, and is more particularly designed as an improvement in that class of switches intended for use upon street-railways.

The object of the present invention is to provide an improved form of switch comprehending in its structure improved means whereby the same may be readily operated from the platform of a car, and, furthermore, the invention aims to provide simple and improved means designed to be carried by the car whereby the operator of the latter may readily throw the switch for opening and closing the same and permit the car passing onto a siding.

With these and other objects in view, which will appear as the nature of the improvements is better understood, the invention consists substantially in the novel construction, combination, and arrangement of parts, as will be hereinafter fully described, illustrated in the accompanying drawings, and pointed out in the appended claims.

In the drawings, Figure 1 is a top plan view of the herein-described switch and the means for operating the same, the same being shown in its closed or normal position. Fig. 2 is a longitudinal section through the same; and Fig. 3 is an end elevation of a car, partly in section and illustrating the means carried thereby for operating the switch.

Referring to the drawings, the numeral 1 designates the rails of a main track, and 2 the rails leading into a siding. Pivotedly connected, as in the usual manner, is a switch-point 3, which point is connected to one of the main rails 1 in order that the passing car may be transferred onto the siding 2.

The preceding description relates to an ordinary form of track-siding. The latter therefore needs no further description. The present invention, however, relates more particularly to the means for shifting the point 3,

and the same consists of an angle-lever 4, mounted upon and movable with a standard 5, mounted at its ends within the casing 6. The lever 4 is suitably connected to the standard 5, so that when said lever is moved, as will more fully hereinafter appear, the standard 5 is adapted to move therewith. Secured to the lower end of the standard 5 is a transversely-extending draft-arm 7, to the ends of which are connected draft-links 8, the latter being crossed, as clearly shown. The opposite ends of the links 8 are loosely connected to a shifting-lever 9, which comprises a longitudinally-extending portion 10 and laterally-projecting arms 11, to the other ends of which the links 8 are connected. It will be observed at this point that each of the links 8 is provided with a buffer-spring 12, which springs are arranged intermediate the ends 65 of said links, and the purpose of these springs is to relieve said links of strain and jar incident to the shifting of the lever 4 by the operating devices carried by the car. It will also be observed that the shifting-lever 9 is 75 provided with diverging braces 13, extending from the ends of the arms 11 and suitably connected to the longitudinally-extending portion 10, whereby the arms 11 are greatly strengthened, and loosely attached to the rear 80 end of the portion 10 is a connecting-link 14, which link is also attached to the switch-point 3. The lever 4 and the shifting-lever 9 are pivotally mounted, as at 15, to the base-board 16, which board may either be arranged upon 85 the surface of the road-bed or disposed beneath the surface thereof.

For the purpose of operating the mechanism just described a pair of vertically-extending contact-rods 17 is carried by the platform 90 of the car, as clearly shown in Fig. 3, and each of said rods passes through the platform of the car and has its lower end turned upwardly to form an engaging shoe 18, these shoes 18 being adapted to contact with the 95 diverging arms of the lever 4 according to the direction in which it is desired to shift the car. A coil-spring 19 also encircles each of the rods 17 for retaining the latter normally in elevated position, and thereby free from 100 engagement with the lever 4, and said springs 19 are disposed within a boxing 20, arranged

at the under side of the car, the lower ends of the springs 19 bearing against the bottom of said box and having their upper ends engaging suitable stops 22, carried by the rods 17.

5 From the foregoing description it will be seen that with the mechanism in the position shown in Fig. 1 the switch-point 3 is in its normal position or closed, and in the event that it is desired to transfer a car from the 10 main line 1 to the siding 2 the same may be readily accomplished by depressing the contact-rod 17 which is farthest from the side of the main line 1 wherein the switch-point 3 is located, such depression so positioning 15 the shoe 18 of said rod in such relation as to readily engage the adjacent arm of the lever 4, and when the contact takes place between said shoe and said arm the lever 4 is swung upon its pivot, through which movement the 20 shifting-lever 9 is moved in a direction opposite to the direction of movement of said lever, with the resultant swinging of the shifting-lever upon its pivot. Such swinging movement opens the switch, and the car is therefore 25 by adapted to pass from the main line to the siding. When in this latter position and a car subsequently approaches the switch, the latter may be closed by depressing the contact-rod 17, which is adjacent to the side of 30 the main line in which the point 3 is arranged, whereupon the lever 4 is engaged, and the same, together with the shifting-lever 9, moved in a direction reverse to the direction of movement when the switch is opened. Accordingly 35 the point 3 is again swung to the position shown in Fig. 1 and the car adapted to continue its course upon the main line.

Having thus fully described my invention,

what I claim as new, and desire to secure by Letters Patent, is—

40

1. In a railway-switch, the combination with a switch-point; of operating means therefor comprising a pivotally-supported standard; a draft-arm projecting from opposite sides thereof; an angle-lever fixed to the 45 standard above the draft-arm and adapted to be struck by devices on a car; a shifting-lever centrally pivoted and consisting of a longitudinally-extending portion and laterally-extending arms; crossed links connecting 50 the ends of said arms with the draft-arms; and a link connection between the switch-point and shifting-lever.

2. In a railway-switch, the combination with a switch-point, of a casing located between the rails of a track; a standard pivotally supported in bearings of the casing; a draft-arm projecting from opposite sides of the standard; an angle-lever fixed upon the standard above the draft-arm and adapted 60 to be struck by devices carried by a car; a pivoted shifting-lever consisting of a longitudinally-extending portion, and laterally-projecting arms, inclined braces between said arms and longitudinally-extending portion; 65 a link connection between the switch-point and shifting-lever; and crossed links connecting the ends of the arms of the shifting-lever, with the ends of the draft-arm.

55

In testimony whereof I affix my signature 70 in presence of two witnesses.

MARQUESS D. MOORE.
